UNITED STATES PATENT OFFICE.

BARNET W. McLEAN, OF PHILADELPHIA, PENNSYLVANIA.

DESIGN FOR A CHAIR.

Application filed July 7, 1927. Serial No. 22,689. Term of patent 14 years.

To all whom it may concern:

Be it known that I, BARNET W. McLEAN, a citizen of the United States, and a resident of Philadelphia, county of Philadelphia, State of Pennsylvania, have invented a new, original, and ornamental Design for a Chair, of which the following is a specification, reference being had to the accompanying drawing, forming a part thereof.

The figure represents a perspective of a chair embodying my new design of the present invention.

I claim:—

The ornamental design for a chair substantially as shown.

BARNET W. McLEAN.
